UNITED STATES PATENT OFFICE.

FRED M. OPITZ, OF MILWAUKEE, WISCONSIN, ASSIGNOR TO HEXCEL RADIATOR COMPANY
SAID WALTER W. WESCOTT.

RADIATOR.

Application filed April 22, 1926. Serial No. 103,796.

My invention pertains in general to automobile radiators. Specifically, the present invention contemplates the provision of a novel and improved radiator fin.

5 In the ordinary fin and tube type of radiator, the fins thereof are not self-supporting but are dependent upon the tubes for their support. I propose to provide an improved tubular radiator unit wherein the fins 10 are not dependent upon the tubes for their support, the tubes being utilized as guiding elements for the proper location and setting up of the radiator fin into a rigid construction. In my construction the tubes are 15 fastened to the fins which are self-supporting.

Heretofore, in this type of radiator, the only practical way of making the construction a strong and rigid one was to dip the construction in a bath of solder. In other 20 words, it has been impossible to produce a satisfactory tubular radiator without dipping the face thereof into solder. Obviously, such use of solder causes the radiator to be less efficient as a cooling medium inasmuch 25 as the portions which have been covered with solder are thicker and hence less conductive. Also these portions are less conductive because of the lower heat conductivity of solder as compared with brass or copper.

30 The construction I provide does not require that it be dipped into a bath of solder in order to give it rigidity and mechanical strength as it is inherently self-supporting without solder. I preferably employ tinned tubes in 35 my radiator unit which may be fastened to the rigid radiator structure by baking the entire unit in a suitable oven for a given period of time. Obviously, if desired, I may dip all or a part of the radiator in solder 40 without deviating from my invention. The strength and rigidity of my improved unit resides in the fin construction itself; the fins being assembled in such a manner that the construction is inherently strong and rigid.

45 In the structure of my invention, the fins are adapted to interlock and are self-aligning. Moreover, due to the interlocking feature the fins are caused to be self-supporting and hence are inherently rigid and possessed 50 of relatively great strength. The fins may be assembled in interlocked position independently of the tubes and the tubes then threaded through the aligned openings. Also the cores or sections may be assembled 55 into a unit of any predetermined depth with-

in limits. Since the interlocking fins are self-supporting, no undue strains or stresses are imposed on the tubes by stresses on the core as has been the case in the past.

In accordance with the general features of my invention, there is provided a tubular radiator unit comprising a plurality of sheet metal fins, each of the fins being furnished with a plurality of transverse protuberances for properly spacing it from the adjacent fin, and a plurality of apertures, each having a lateral extension adapted to enter into a telescoping relation with a similar extension on a contiguous fin, and a plurality of tubes positioned within the said apertures and fastened to the said fins. The tubes in addition to serving as conduits for the water also serve as guiding elements for enabling the proper alignment and assembly of the fins. Then, too, the telescoping extensions of the fins surrounding the tubes do not impose any undue stresses or strains on the tubes inasmuch as the fins are self-reinforced and self-supporting.

The novel fins of my construction are 80 formed of comparatively thin sheet material such as brass, copper or bronze sheets. I preferably secure the tubes to the interlocking fins by tinning the tubes prior to assembling them into the radiator unit. After 85 the unit is assembled it is preferably baked to about 460° F. in any conventional oven. The baking action causes the tin or solder on the tubes to not only fasten the interlocking portions of the fins together, but serves to 90 fasten the tubes to the interlocking portions.

Other objects and advantages of my invention will more fully appear from the following detailed description taken in connection with the accompanying drawings which illustrate several embodiments thereof, and in which,

Figure 1 is a view of a strip of sheet material from which my novel fin is formed;

Fig. 2 is a plan view of the strip after a forming operation has been performed illustrating the first step involved in the manufacture of my novel fin;

Fig. 3 is a sectional view taken on the line 3—3 of Figure 2 looking in the direction indicated by the arrows;

Fig. 4 is a view illustrating the second step involved in the manufacture of the fin;

Fig. 5 is a view illustrating the finished fin;

Fig. 6 is a sectional view taken on the line 6—6 of Figure 5 looking in the direction indicated by the arrows;

Fig. 7 is a sectional view taken on the line 5 7—7 of Figure 5;

Fig. 8 is a sectional view taken on the line 8—8 of Figure 5;

Fig. 9 is a sectional view illustrating the manner in which the radiator tubes are 10 mounted in my novel fins;

Fig. 10 is a view illustrating a plurality of fins piled one upon another with the tubes extending therethrough;

Fig. 11 is a sectional view taken on the line 15 11—11 of Figure 9 looking upwardly;

Fig. 12 is a sectional view taken on the line 12—12 of Figure 10;

Fig. 13 is a view illustrating how the units may be associated with each other;

20 Fig. 14 is a plan view of a modified form of fin;

Fig. 15 is a sectional view taken on the line 15—15 of Figure 14;

Fig. 16 is a view partly in section illustrating how the tubes are mounted in the modified form of fin;

Fig. 17 is a sectional view taken on the line 17—17 of Figure 16 looking in the direction indicated by the arrows; and

30 Fig. 18 is a sectional view taken on the line 18—18 of Figure 16.

Referring now to the drawings in detail in which like reference numerals designate similar parts throughout the several views, 20 35 denotes generally a strip of sheet material (Figure 1), from which my novel fin is formed. The material employed may be of bronze brass, copper, or any other suitable material. The first step involved in the 40 manufacture of the novel radiator fin is to pass this material through suitable drawing or stretching mechanism to produce the construction illustrated in Figure 2.

As best shown in Figures 2 and 3, it will be 45 noted that the first step in the process of manufacturing my novel radiator fin, consists in forming or rolling the sheet in such a manner that it will be furnished with a plurality of polygonal shaped protuberances 21. 50 These protuberances are formed preferably by drawing or stretching the metal so as to increase the cooling area afforded by the strip or ribbon 20 without changing its length or width. For example, let us assume that the 55 ribbon 20 is one inch wide and ten inches long. Now, when the protuberances are formed in the sheet 20, this fin or sheet will present, for example, 15 square inches of cooling surface without having added or used any additional 60 metal.

Each protuberance comprises a plurality of slanting sides 22 and a substantially flat top 23. The top 23 is disposed in substantially the same plane as the strip. Each pro-

65 tuberance 21 is spaced from the adjacent protuberances 21 by transverse horizontal spaces 24. The protuberances are spaced equi-distantly apart and their size depends upon the size of the radiator tube to be used in the radiator unitary construction. The protuberances are defined on their end sides by a 70 pair of longitudinal flanges 25. Each of the flanges 25 may be formed substantially flat or slanting. In the preferred embodiment of 75 my invention, I form these flanges into beads as indicated at 26 in Figure 8. The forming of the flanges 25 into beads may be done contemporaneously with the forming of the protuberances 21 or on the other hand they may be formed separately and by independent 80 forming mechanism.

In Figures 4 and 5, I have illustrated the next two steps involved in the manufacture of my radiator fin. The first step consisted in forming the protuberances 21. Now, the 85 next step consists in slitting the protuberances as indicated at 30 in Figure 4. Each slit 30 is located substantially transverse to the direction of the strip and is disposed in a substantially central position with respect to the top 23 of each protuberance. The slit 30 may be formed by any suitable slitting mechanism. At the same time that the slit 30 is made, I also provide the spaces 24 with transverse slits 31. The slits 31 are parallel to the 90 slits 30 and are preferably the same size as the slits 30. Thus, it will be seen that the slits 30 are separated from each other by the slits 31, or in other words, the slits 30 and 31 alternate throughout the entire strip. 95

In Figure 5, I have illustrated the third and last step involved in the manufacture of the radiator fins. This step consists in forming the slits 30 and 31 into apertures or openings 32 and 33, respectively. These apertures or openings 32 and 33 are adapted to accommodate the tubes of the radiator. As best shown in Figure 6, the openings 32 are each defined by a laterally extending flange 34. This flange 34 extends inside of the protuberance 21, so to speak, and is preferably disposed at right angles to the plane of the fin. It will be seen therefore that no material is punched from the strip in order to form the opening 32. On the contrary, the material pushed out of the way in this forming operation is utilized to create the flange 34 which is adapted to interlock with a similar flange on an adjacent fin as will be more fully explained hereinafter. This forming 110 of the flange 34 is made possible by first slitting the protuberances 21 as has already been described.

Now, the slits 31 are formed into the apertures 33 which are somewhat smaller than the apertures 32. The apertures 33 are each defined by a lateral flange 35 disposed at right angles to the plane of the fin. This flange 35 125

is adapted to telescope an aperture 32 as will become obvious from the description to hereinafter follow.

Now as best shown in Figure 9, the apertures or openings 32 and 33 are adapted to receive radiator tubes 40. The tubes 40 are spaced substantially equidistantly apart and are disposed substantially parallel to each other. The ends of the tubes may terminate 10 in suitable headers in any conventional manner. Although the tubes 40 may be made of any suitable or desirable material, I preferably provide each of them with a coating of tin for a purpose to be hereinafter explained 15 in detail. In assembling the radiator units, the tubes are placed in one of the radiator fins and the fins are piled one upon another. In other words, the assembling operation involves merely a pile-up operation.

20 The fins are piled one upon another in such a manner that the flange 34 of each opening 32 is adapted to be telescoped by the flange 35 of each opening 33. In other words, the flanges 35 telescope the flanges 34 as best 25 shown in Figure 11. This results in each fin being staggered with respect to the adjacent fin. Then, too, the telescoping portions 34 and 35 surround the corresponding tube 40. This telescoping feature enables the fins 30 to be interlocked and insures of their proper alignment. Furthermore, the telescoping feature permits of a more rigid and strong structure than has heretofore been possible. Also, the fins are not dependent upon the 35 tubes 40 for this support, inasmuch as they are self-supporting. In fact, as will be explained hereinafter, the tubes are, in reality, fastened to the telescoping portions of the fins. The fins may be assembled into units 40 of any predetermined or desired depth depending upon the size of radiator required. Moreover, since the interlocking fins are self-supporting no undue strains or stresses are imposed upon the tubes by the fins as has been 45 the case in the past. The tubes 40 in addition to serving as conduits for conveying steam and water serve as guides for enabling the proper alignment and setting up of the fins into a unitary radiator structure.

50 As best shown in Figure 11, it will be observed that the protuberances 21 alternate with the spaces 24. This results in the fins giving the radiator unit a cellular effect. The cells formed by the alternating protuberances 55 are somewhat polygonal in shape. Moreover, it should be noted that the protuberances of one fin are staggered with respect to the protuberances of the adjacent fin so as to permit of the previously described telescoping action. 60 After the fins and tubes 40 have been assembled together into a unitary structure the next step is to fasten the tubes to the fins. I preferably fasten the tubes to the telescoping portions of the fins which fastening also serves 65 to secure the flanges 34 to the flanges 35, thus

creating a rigid construction. Inasmuch as the tubes 40 are tinned before they are assembled into the unitary structure, it will of course be apparent that by heating the tubes the tin coating will serve to fasten the telescoping portions together and to the tubes. In practice, I have attained excellent results by baking the assembled units in an oven to a temperature of approximately 460° F. After the baking operation it will be found 70 that all of the fins are interlocked as well as fastened to the tubes. I desire it understood however that the fins support themselves and are not dependent upon the tubes 40 for reinforcement. This construction minimizes the 75 possible strain or stresses which might be imposed on the tubes 40.

The previously described baking operation eliminates the necessity of having to dip the face of the radiator construction into a bath 80 of solder in order to secure the fins to the tubes. By obviating the necessity of having to solder the fins to the tubes, the exposed area of the radiator is greatly increased thereby resulting in a more efficient cooling medium. That is to say, the efficiency of the 85 radiator depends upon the area of the exposed radiator fin and obviously by increasing this area a greatly improved construction will be 90 created.

The finished radiator unit may be mounted in suitable headers, either as a single unit or in multiple, as illustrated in Figure 13. In this illustration, it will be evident that the beaded portion 26 of each unit abuts a beaded portion of the adjacent unit. If it is desired, these beaded portions may be secured to each other in any suitable manner. This will permit of a rigid radiator composed of a plurality of radiator units embodying the features of my invention.

I have illustrated a modified form of my invention in Figures 14 to 18 inclusive. This form of the invention is very much similar to the previously described form and has several features in common with the other form of my invention.

The fin illustrated in Figure 14 has a plurality of polygonal shaped protuberances 41 which alternate with apertures 44. The protuberances 41 may be formed by any suitable mechanism, such, for example, as a rolling mill or a punch press. The apertures 44 in this construction are not defined by annular flanges. On the contrary the material is punched free from the strip of material in order to form the apertures 44. In other words, the apertures 44 are formed by punching a plurality of blanks from the strip of material. Referring to Figure 15, I have 115 illustrated in dotted lines at 40' the part that has been blanked from the strip in order to form an aperture 44. The part 40' prior to the blanking operation cooperates with the 120 adjacent sides 42 to form another protuberance 125 130

ance which projects from the sheet in an opposite direction to that of the protuberance 41. That is to say, the strip after the forming operation has a somewhat corrugated appearance. Thus it will be apparent that the aperture 44 is not disposed in the plane of the strip but is positioned laterally from the sheet in much the same manner as the tops 43 of the protuberances 41. The protuberances 41 and 10 40' are in reality staggered with respect to each.

Also, it should be noted that the protuberances 41, in this construction, are not supplied with apertures as in my other modification. 15 Each protuberance comprises a plurality of slanting sides 42 and a substantially flat top 43. The alternating apertures and protuberances are defined on their sides by a pair of flanges 45 which may be also formed in any 20 desirable manner. The apertures 44 are of a sufficient size to accommodate the tubes 46. The tubes 46 are spaced equi-distantly apart and are disposed parallel to each other. The fins and tubes are assembled together in much 25 the same manner as those of my preferred embodiment of the invention. In the present construction however, the protuberances 41 are disposed immediately over each other. Then, too, every other fin in the unitary structure 30 is positioned upside down with respect to the other fin so as to enable the tops 43 of the protuberances 41 to engage with each other. This will result in the fins assuming a somewhat cellular appearance. The cells 35 are polygonal in shape and it takes two fins to create a given set of cells.

The fins and tubes in my modified form of the invention may be secured together by dipping the pile-up assembly into a bath of 40 solder. Obviously, the solder adhering to the fin construction will serve to fasten the tubes 46 to the fins, as well as to fasten the tops 43 of the protuberances together. Then, too, the sides 42 defining the apertures 44 will be 45 secured together at the tubes 46.

The modified unitary construction may be assembled into a radiator composed of a plurality of units in much the same manner as was discussed in connection with the illustration 50 in Figure 13. The flanges 45 of one unit may, if it is so desired, be secured to the flanges 45 of the adjacent unit.

Now, of course, I desire it understood that although I have described in detail several 55 embodiments of my invention, the invention is not to be limited thereby but only in so far as defined by the scope and spirit of the appended claims.

I claim:

60 1. As an article of manufacture, a radiator fin comprising a strip of thin sheet material having formed therein a plurality of apertures each of which is defined by a laterally extending flange, alternate apertures being of one size and the other apertures being of

a different size the flange defining the smaller aperture being shaped to fit relatively tight about a radiator tube and the flange defining the larger of said apertures being shaped to receive a flange about one of the smaller 70 apertures of a similar fin.

2. As an article of manufacture, a radiator fin comprising a thin strip of sheet material having formed therein a plurality of transverse protuberances each of which is 75 equipped with an aperture, said aperture being defined by a flange extending in an opposite direction to that of the protuberance, said flange being cooperable with an aperture in a part of an adjacent fin. 80

3. As an article of manufacture, a radiator fin comprising a strip of thin sheet material having formed therein a plurality of transverse protuberances extending laterally therefrom and a plurality of apertures alternating 85 with the said protuberances, each of the said protuberances having formed therein an aperture, said several apertures in the protuberances disposed in a plane parallel with that of the other apertures, the apertures in the 90 protuberances being larger than those between the protuberances.

4. As an article of manufacture, a radiator fin comprising a strip of thin sheet material, having formed therein a plurality of alternating 95 protuberances and apertures, each of the protuberances being provided with an aperture of a larger size than the other apertures, each of all the apertures being defined by a laterally extending flange for receiving 100 a radiator tube.

5. As an article of manufacture, a radiator fin comprising a strip of thin sheet material, having formed therein a plurality of transverse protuberances extending laterally therefrom and a plurality of apertures alternating 105 with the protuberances, each of said apertures being defined by a laterally extending flange projecting in a direction opposite to that of the protuberance. 110

6. As an article of manufacture, a radiator fin comprising a sheet of thin metallic material having formed therein a plurality of transverse protuberances extending laterally therefrom and a plurality of apertures, alternate apertures being of one size and the other apertures being of another size, each of the apertures being defined by a laterally extending flange adapted to receive a radiator tube 115 the flange associated with each of the larger apertures being shaped similar to and slightly larger than the flange associated with the smaller aperture, said larger flanges being capable of receiving the smaller flanges of a similar fin. 120

7. In a tubular radiator unit, a plurality of fins piled one upon another, each of the said fins being equipped with a plurality of apertures, a plurality of protuberances for engagement with and for spacing it from the 130

adjacent fins and a plurality of lateral flanges adapted to cooperate with the flanges of the adjacent fins to interlock the fins, and a plurality of tubes positioned within the apertures and fastened to the said fins.

8. In a tubular radiator unit, a plurality of fins piled one upon another, each fin having a plurality of apertures, each aperture being defined by a laterally projecting flange adapted to cooperate with a flange of an adjacent fin to interlock the fins, and a plurality of tubes extending through the apertures of the interlocked fins, alternate flanges of each fin being disposed in and cut by one plane and the other flanges of the fin being disposed in and cut by a second plane parallel to said first plane.

9. In a tubular radiator unit, a plurality of fins piled one upon another, each fin having a plurality of apertures, each aperture being defined by a laterally projecting flange adapted to enter into a telescoping relation with a flange of an adjacent fin to interlock the fins, and a plurality of tubes extending through the apertures of the interlocked fins, alternate flanges of each fin being disposed in and cut by one plane and the other flanges of the fin being disposed in and cut by a second plane parallel to said first plane.

10. In a tubular radiator unit, a plurality of fins piled one upon another, each fin having a plurality of apertures, alternate apertures being formed in protuberances extending laterally from the fins, said protuberances serving to space the fins, each aperture being defined by a laterally projecting flange adapted to enter into a telescoping relation with a flange of an adjacent fin to interlock the fins, and a plurality of tubes extending through the apertures of the interlocked fins.

11. In a tubular radiator unit, a plurality of fins piled one upon another, each of the said fins having a plurality of alternate apertured protuberances and openings, the apertures in the protuberances being larger than the openings, each opening being defined by a laterally extending flange adapted to telescope the apertures in the contiguous protuberance of an adjacent fin, and a plurality of tubes extending through the said apertured protuberances and openings.

12. As an article of manufacture, a radiator fin comprising a narrow strip of thin sheet metal, said strip having substantially straight edges and having a series of frustum-shaped projections extended outwardly from the plane of the strip along the central part of the strip for engagement with adjacent fins to space the same and to provide additional cooling surface, said strip having apertures therethrough for receiving vertical water tubes.

13. In combination, a plurality of fins comprising strips of thin sheet metal, said strips having substantially straight edges and each having a row of relatively large protuberances along the central part of the strip, the protuberances of each fin extending into engagement with an adjacent fin to form spacing means, said fins having aligned openings and a series of flat vertical water tubes extending through the aligned openings, said tubes being embraced by the edges of the sheet about the openings in the fins to form unions therewith, said unions being of less length along the tube than the extension of said protuberances from the body of the corresponding fin.

In witness whereof, I hereunto subscribe my name this 13 day of April, 1926.

FRED M. OPITZ.
